GAS BURNER

Thomas I. Forster, Berkeley, Calif.

Application March 14, 1934, Serial No. 715,464

2 Claims. (Cl. 158—11)

This invention relates to burners utilizing natural or manufactured gas as a fuel.

It is the principal object of the present invention to provide an improved burner of the character referred to, by means of which an extremely high temperature flame may be created with a minimum of fuel under a comparatively low pressure.

In practicing the invention, I fit a burner head 10 with a Venturi tube. The gas is delivered through a jet projecting centrally within the venturi, the Venturi tube being formed with shutter controlled primary air ports surrounding the jet so that the jet will draw in a maximum of primary air into the venturi for combustion purposes. I have also provided a means of injecting steam, air or oil under pressure at high velocity into the venturi surrounding the jet to increase the temperature of the flame.

One form which the invention may assume is exemplified in the following description and illustrated by way of example in the accompanying drawing, in which:

Fig. 1 is a view of my improved burner with parts thereof broken away and in section to disclose certain features of construction.

Fig. 2 is an enlarged view in central section through the injector head.

Fig. 3 is an end view of the injector head, of the nozzle end thereof.

Fig. 4 is an enlarged view showing the manner in which the orifice fitting is connected to the injector head.

Referring more particularly to the accompanying drawing, 10 indicates a gas burner head of any preferred type or design. To the inlet end of this head, the discharge end of a Venturi tube 11 is connected. The opposite or intake end of the Venturi tube is formed with a series of primary air ports 12 which surround a central boss 14. A manually operative shutter 15 is fitted to the intake end of the Venturi tube to control the primary air ports 12. By means of this shutter 15 the effective area of the ports 12 may be regulated, or, in fact, they may be entirely closed.

Connected to the central boss 14 is an injector head 16. At one end, this head is formed with a threaded nipple 17, which is threaded into the boss 14. The other end of the head is formed with a threaded nipple 18 which may be connected with a valve 19. Connected to the opposite or inlet side of this valve 19 is a pipe 20, which may be led to a source of natural or manufactured gas under a desired pressure. Intermediate the nipples 17 and 18 the injector head is formed with

an enlarged chamber 21, with which a port 22 communicates. This port 22 is interiorly threaded and is surrounded by a boss 23 so that a delivery pipe 24 may be connected therewith for delivering air, steam or oil under pressure to the enlarged chamber 21, as will be hereinafter described.

Secured in the nipples 17 and 18 is a gas delivery tube 25, which extends centrally through the enlarged chamber 21 and which is so connected to the nipples 17 and 18 as to maintain the interior of the chamber 21 out of communication with the interior of the tube 25.

It will be noticed that the nipple 17 is counter-bored inwardly from its outer end in order that an orifice fitting 26 may be removably fitted to the end of the tube 25 within the nipple 17. The interior wall of the nipple 17 surrounding the tube 25 is formed with a series of inspirator orifices 27 arranged in circular fashion about the tube 25 and communicating at one end with the interior of the chamber 21 and at the other end with the chamber formed in the nipple 17 by the counter-boring thereof. The manner in which this orifice fitting 26 is constructed and connected to the tube 25 is clearly illustrated in Fig. 4. By making this orifice fitting 26 removable, the diameter of the orifice through which gas is injected into the venturi 11 may be readily changed.

Referring to Fig. 1, it will be seen that the pipe 24 is fitted with a cross 25a. To this cross is connected a valve controlled pipe 28, which is connected with a source of air under pressure, and with a valve controlled pipe 29 which is connected with a source of steam under pressure. The remaining port of the cross 25a is connected with a valve controlled pipe 30, which is connected with a source of fuel oil under suitable pressure.

To operate the burner, the shutter 15 is actuated to open the ports 12, and the valve 19 is then opened to enable gas under pressure to pass through the tube 25 in the injector head 16 and discharge at comparatively high velocity through the orifice in the orifice fitting 26 into the Venturi tube 11. The discharging of this gas at high velocity into the Venturi tube 11 draws primary air through the shutter-controlled ports 12 into the venturi in sufficient quantity to form a proper combustible mixture to be delivered to and ignited at the burner head 10.

If a flame of higher temperature is desired, either air or steam under pressure may be delivered through the pipe 24 to the chamber 21 so that it will discharge through the orifices 27 into the venturi. The velocity of the streams of either

air or steam, or both, discharging into the venturi increases the amount of primary air drawn in through the ports 12 to aid in the combustion of the gas. This creates the same result as increasing the gas pressure.

If a flame of still higher temperature is desired, oil may be introduced into the chamber 21 of the injector head, together with steam under pressure, which acts to atomize the oil, this mixture passing through the orifices 27 into the venturi 11, acting as before to draw in a maximum quantity of primary air through the ports 12 and at the same time aid in increasing the temperature of the flame.

15 It is obvious from Fig. 1 that by manipulating the valves of the pipes 28, 29 and 30, air, steam or oil may be admitted to the chamber 21 of the injector head, as desired.

In the event the burner is to be used in heat-treating, the shutter 15 is moved to close the ports 12. In this circumstance, either air or steam under pressure is used in conjunction with the gas for combustion purposes.

20 In those instances where no air should be employed, the shutter 15 is used to close the ports 12 and the auxiliary steam is delivered to the chamber 21 and discharged into the venturi 11 through the orifices 27 to aid in the combustion of the gas. Oil may also be injected with the 25 steam, if desired.

From the foregoing it is obvious that I have provided a very efficient burner for utilizing gas as a fuel, by means of which burner flames of comparatively high temperatures may be obtained with a minimum fuel consumption, and which burner is of comparatively simple construction and is inexpensive to manufacture.

30 While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. An apparatus of the character described, including a gas burner head, a Venturi tube connected at its outlet end to said head, the intake end of said Venturi tube being formed with a series of primary air ports, a manually operative shutter controlling the effective area of said ports, an injector head connected to said inlet end of the Venturi tube centrally thereof, an orifice fitting carried by said injector head and having an orifice formed therethrough for delivering gas into the venturi at high velocity, said injector head having a passageway formed therethrough for delivering gas to the orifice fitting, said injector head having a chamber formed therein and separated from the gas passageway, and means for separately delivering air under pressure, steam or fuel oil to said chamber, and said injector head having a series of orifices adjacent to 20 and surrounding said orifice fitting whereby fluid under pressure in said chamber will discharge into the venturi at high velocity.

2. An apparatus of the character described, including a gas burner head, a Venturi tube connected at its outlet end to the said head, the intake end of said Venturi tube being formed with primary air ports, an injector head connected to said inlet end of the Venturi tube centrally thereof, an orifice fitting carried by said injector head 25 and having an orifice formed therethrough for delivering gas into the venturi, said injector head having a passageway formed therethrough for delivering gas to the orifice fitting, said injector head having a chamber formed therein and separated from the gas passageway, and means for separately delivering air under pressure, steam or fuel oil to said chamber and said injector head having a series of orifices adjacent to said orifice fitting whereby fluid under pressure in said chamber 30 will discharge into the venturi at high velocity.

THOMAS I. FORSTER.
